[57] CLAIM

The ornamental design for a combined display rack and light fixtures therefor, as shown and described.

DESCRIPTION

FIG. 1 is a perspective view of a combined display rack and light fixtures therefor showing my new design;
FIG. 2 is a side elevational view taken from the right of FIG. 1, the side opposite being a mirror image thereof;
FIG. 3 is a top plan view thereof;
FIG. 4 is a bottom plan view thereof.
